UNITED STATES PATENT OFFICE.

CLARENCE H. WOLFE, OF CINCINNATI, OHIO, ASSIGNOR TO REMINGTON RAND INC.,
OF TONAWANDA, NEW YORK.

TYPE-SWAGING MACHINE.

Application filed October 1, 1927. Serial No. 223,430.

This invention relates to type swaging machines and particularly to mechanism for holding type blanks on bars and feeding them into cooperative relation with the dies, 5 and then ejecting them after the swaging operation has been performed.

One object of the invention is the provision of means for automatically clamping the blanks or bars in position on a head as they 10 are moved into cooperative relation with the dies.

Another object is the provision of means for automatically releasing the clamps as the clamping head is moved away from the dies 15 after the swaging operation has been performed.

Other objects will be apparent from the following description taken in connection with the drawings in which:—

20 Fig. 1 is a top plan view of the clamping head.

Fig. 2 is a side view of the clamping head, with a part of one of the arms of the head broken away.

25 Fig. 3 is a face view of one of the arms of the clamping head.

Fig. 4 is a section on the line 4—4 of Fig. 3.

Fig. 5 shows the means for alining the 30 head as it is moved into swaging position.

The drawings show only so much of the machine as is necessary to disclose this improvement.

The shaft 10, (Figs. 1 and 2), is mounted 35 in a carriage 11 slideable on a support 12. Means, not disclosed, is provided for moving the carriage to the right to the position shown in Figs. 1 and 2 and then to the left to its home position. Any suitable rack and 40 gearing construction may be provided to rotate the shaft one-quarter turn clockwise, (Fig. 2), as the carriage is moved toward the left to its home position.

The shaft 10 carries a clamping head 45 15 provided with four arms 16 of identical construction.

Each arm 16 carries a clamp housing 17 suitably secured thereto by screw bolts 18, (Fig. 3). Each housing is provided with 50 two recesses 20 receiving pairs of clamping blocks 21 and 22 pressed apart by springs 23 suitably anchored to the block 22 as shown in Fig. 4. The block 22 is held stationary 55 by a screw bolt 24 passing through the housing 17. The block 21 is moved toward the

block 22 by a wedge 25 which cooperates with an edge of the block and a wedge face 26 constituting one side of the recess 20. The blocks 21 and 22 are provided with co-operating wedge faces 27 and 28 to force the 60 block 21 laterally as it is forced toward the block 22, the block 21 being shorter than the recess 20 to permit such movement. The blocks 21 and 22 define "blank" holding recesses 29. The construction is such that 65 pressure will be applied to four sides of the blanks.

The wedges 25 for each pair of clamping blocks are arranged as shown in Fig. 3 and are forced away from each other to actuate 70 their respective blocks 21 by a double wedge faced plunger 30, (Figs. 2 and 3), suitably guided in a slot in the housing and retained therein by a limiting screw bolt 31 secured in the housing and cooperating with a 75 slot in the plunger. The plunger is normally urged into its outer position by a spring 32 mounted in a hole in the housing and suitably retained therein by a screw 80 plug 33.

One end of the plunger 30 projects through the housing and is provided with a head 35 (Figs. 1, 2 and 3), cooperating with the end of a plate 36, secured to raised seats 37 on the support 12 by bolts 38 and constantly 85 urged downwardly by springs 39 on bolts 40 screwed into said seats. The plate 36, (Figs. 1 and 2), bears on cylindrical fulcrum rods 44 seated in correspondingly formed recesses in the plate 36 and seats 37 at a point 90 midway between the bolts 38 and 40. The bolts 38 and 40 are equipped with adjusting nuts 45 by means of which the plate 36 may be adjusted about a horizontal axis and the proper compression placed on the springs 95 39. Lock nuts 46 cooperate with the nuts 45 to maintain such adjustment.

The left hand end of the plate 36, (Fig. 2), is provided with a wedge face 50 against which the head 35 of the plunger 30 is 100 moved as the clamping head 15 is moved into the swaging position shown in Figs. 1 and 2. The wedge face 50 depresses the plunger 30 and, as is apparent from Fig. 3, clamps the blanks securely in position for the swaging operation. The springs 39 hold the plunger depressed until the clamping head is moved toward the left.

After the swaging has been performed, 110 the clamping blocks 21 are permitted to be

moved into their releasing position by the springs 23. As the clamping head 15 is moved toward the left, the plunger head 35 is moved away from the plate 36 and the 5 plunger 30 is restored by its spring 32. This frees the wedges 25, (Fig. 3), which may now be moved toward each other to release the blocks 21 by plungers 54 suitably supported in the clamp housing 17, each having its inner end engaging the small end of its corresponding wedge 25 and its outer end projecting beyond the housing and provided with a conical head 55 to wedgingly engage with wedges 56, (Figs. 1 and 2) on the support 12 as the clamping head 15 is rotated during its movement to the left into its home position. This permits the swaged type bars to drop out of the clamping blocks.

Each clamping arm 16 is suitably recessed 20 to receive two ejecting plungers 60, (Figs. 1, 2 and 3), each of which as shown in Fig. 3, over-lies the recesses 29 in a pair of blocks 21 and 22. Cooperating with the pair of plungers 60 in each arm 16 is a plunger 61, 25 (Figs. 1 and 2) slidably mounted in the arm with its ends projecting beyond the lateral sides of the arm.

As shown in Fig. 1, the carriage 11 is provided with a wedge piece 62 suitably secured 30 thereto as by screw bolts 63 and which cooperates with the upper end of the plunger 61 as viewed in Fig. 1 to move the plunger 61 into the position shown in the center of this figure as the clamping head 15 is rotated counter-clockwise. The plunger 61 is provided with a head 64 having one of its sides shaped to conform to the periphery of the hub, (Fig. 2), on the clamping head to hold the plunger against rotation. The 40 plunger 61 is recessed at 65 to cooperate with the rounded ends of the ejector plungers 60. As shown in the left of Fig. 1, the plungers 60 are in their moved position. As shown in the right hand part of this figure, the 45 plungers 60 are in their retracted position. This position they were permitted to assume when the blanks were inserted with the arm 16 under the wedging piece 62 as shown in the center of this figure.

50 After the swaging has been performed, the clamping head is withdrawn and rotated. As it is rotated, a wedging piece 66, (Figs. 1 and 2), on the support 12 raises the plunger 61 which moves the plungers 60 radially 55 outwardly and ejects the swaged type bars.

The clamping head 15, (Fig. 2), is provided with an indexing and alining disc 67 suitably secured thereto by screw bolts 68. The disc is provided with alining notches 69 which cooperate with a fixed aliner 70 as the clamping head moves into swaging position. The aliner is suitably secured to the support 12.

65 Dies may be suitably supported in a carrier 71, (Fig. 1), or block suitably supported

on the main support 12 and operated by any suitable mechanism to perform the swaging or kneading operation on the type blanks or bars.

While, for purposes of disclosure, only one embodiment of a particular form has been shown and described, it is understood that the invention may be susceptible of embodiment in other forms falling within the terms of the claims.

75 I claim:

1. In a machine of the class described, the combination with a rotatable clamping head movable forwardly into swaging position, and rearwardly into home position and rotatable as it moves rearwardly; clamping means carried by said head, and means carried by the machine for tightening said clamping means as the head moves into swaging position.

80 2. In a machine of the class described, the combination with a rotatable clamping head movable forwardly into swaging position, and rearwardly into home position and rotatable as it moves rearwardly; clamping 85 means carried by said head, and yieldable means carried by the machine for operating said clamping means as the head moves into swaging position.

90 3. In a machine of the class described, the combination with a rotatable clamping head movable forwardly into swaging position, and rearwardly into home position and rotatable as it moves rearwardly; clamping 95 means carried by said head, a plate pivotally mounted on the machine and adapted to operate said clamping means as the head is moved into swaging position, and spring 100 means opposing the movement of said plate out of its normal position.

105 4. In a machine of the class described, the combination with a clamping head mounted for movement into and out of swaging position; of clamping means carried by said head and comprising a plunger, and wedge shaped 110 means mounted on the machine for operating said plunger as the head moves into swaging position.

115 5. In a machine of the class described, the combination with a clamping head mounted for movement into and out of swaging position; of clamping means carried by said head and comprising a plunger, and a plate pivoted on the machine and provided with a 120 surface inclined to the direction of travel of the head to operate said plunger as the head moves into swaging position.

125 6. In a machine of the class described, the combination with a clamping head mounted for movement into and out of swaging position; of clamping means carried by said head and comprising a plunger, a plate pivoted on the machine and formed to operate said plunger as the head moves into swaging 130 position, means for positively limiting the

pivotal movement of said plate in one direction, and means for yieldingly limiting the pivotal movement of said plate in the opposite direction.

5 7. In a machine of the class described, the combination with a clamping head mounted for movement into and out of swaging position; of clamping means carried by said head and comprising a plunger, a plate 10 operable with said plunger, and yielding means opposing the movement of said plate to yieldingly operate said plunger and hold it in operated position.

8. In a machine of the class described, the 15 combination of a clamping head, a recessed clamp housing rigid therewith, a pair of clamping blocks located in the recess of the housing and provided with opposing surfaces and shoulders for engagement with 20 four sides of a blank, means for automatically moving said blocks relatively toward each other, and means for automatically moving said blocks laterally relatively to each other.

25 9. In a machine of the class described, the combination of a clamping head, a recessed clamp housing rigid therewith, a pair of clamping blocks located in the recess of the housing and provided with opposing surfaces and shoulders for engagement with 30 four sides of a blank, means for automatically moving said blocks relatively toward each other, and cooperating cam elements on said blocks for automatically moving said 35 blocks laterally relatively to each other as they are moved relatively toward each other.

10 10. In a machine of the class described, the combination of a recessed clamp housing, a clamp block secured in the recess of the 40 housing, a cooperating clamp block mounted in the recess of the housing for movement simultaneously toward and laterally relatively to said first clamp block, and means for automatically moving said second clamp 45 block.

11. In a machine of the class described, the combination of a clamping head movable into and out of swaging position, a pair of relatively movable clamp blocks carried by 50 said head supported for movement toward each other and laterally relatively with respect to each other, a wedge for effecting such movement, and means for automatically actuating said wedge as the head moves 55 into swaging position to move said clamp blocks to effect a clamping action.

12. In a machine of the class described, the combination of a clamping head movable into and out of swaging position, a pair 60 of relatively movable clamp blocks carried by said head supported for movement to-

ward each other and laterally relatively with respect to each other, a wedge for effecting such movement, and means for automatically actuating said wedge in the opposite direction as the head moves out of swaging position. 65

13. In a machine of the class described, the combination of a recessed clamp housing, two pairs of clamps within said housing, the 70 clamps of each pair being movable relatively to each other to effect a clamping action, a wedge for each pair of clamps cooperating with the housing and one of the clamps, and a double wedge member cooperating with 75 both of said wedges to simultaneously operate both pairs of clamps.

14. In a machine of the class described, the combination of a recessed clamp housing, two pairs of clamps within said housing, the 80 clamps of each pair being movable relatively to each other to effect a clamping action, a wedge for each pair of clamps cooperating with the housing and one of the clamps, and means for moving said wedges into releasing 85 position.

15. In a machine of the class described, the combination with a laterally shiftable and rotatable clamping head comprising a plurality of clamp housings, clamps within the 90 housing, wedges for operating said clamps, means for automatically actuating said wedges to operate said clamps as the head is shifted into swaging position, and means for automatically actuating said wedges to release said clamps as the head is rotated during 95 its movement into its home position.

16. In a machine of the class described, the combination with a laterally shiftable rotatable clamping head, comprising a plurality of clamp housings; clamps mounted within each housing, means projecting from said housing in the plane of said head for actuating said clamps as the housing moves into swaging position, and means projecting 100 from said housing laterally with respect to said head for releasing said clamps as the head is rotated during its movement into 105 home position.

17. In a machine of the class described, the combination with a main frame, a carriage slidable thereon, and a rotatable clamping head mounted on said carriage; of clamping means carried by said head, wedge means supported on the frame for operating 110 said clamping means as the carriage is shifted, and wedge means also secured to said frame for releasing said clamping means as the head is rotated and shifted to its home position. 115

CLARENCE H. WOLFE.
